UNITED STATES PATENT OFFICE

2,230,135

COOKING TIMER

Jerome De Haes, Chicago, Ill., assignor of one-half
to Albert S. Malecki, Chicago, Ill.

Application July 16, 1938, Serial No. 219,550

3 Claims. (Cl. 200—36)

The invention relates to improvements in timers especially adapted for use in conjunction with stoves for controlling cooking operations, the primary object of the invention being the provision of a construction of the character indicated whereby the length of the cooking operations may be readily controlled and which is of simple construction and highly efficient in use. Other objects will appear hereinafter.

5 The invention consists in the combinations and arrangements of parts hereinafter described and claimed.

10 The invention will be best understood by reference to the accompanying drawings forming a part of this specification and in which

15 Fig. 1 is a face view of an electric clock employed in a timer embodying the invention;

Fig. 2 an enlarged detail face view of the upper portion thereof;

20 Fig. 3 a transverse medial section taken through the clock face;

Fig. 4 an enlarged detail vertical section taken through the upper portion of the clock face;

25 Fig. 5 a section taken substantially on line 5—5 of Fig. 4;

Fig. 6 a section taken substantially on line 6—6 of Fig. 4;

Fig. 7 a top plan view corresponding with Fig. 4; and

30 Fig. 8 a diagrammatic view illustrating the electric circuits employed in the timer.

The embodiment of the invention illustrated in the drawings comprises an ordinary electric clock provided with a face, the central portion

35 10 of which constitutes the usual clock dial. A guide groove 11 is formed in said face outside of said clock dial and extends as shown twice around said dial. A transparent cover 12 is ar-

40 ranged as indicated in Fig. 3 over said clock face and the usual hour hand 13 and minute hand

14 are provided for cooperation with said clock dial. The minute hand shaft 15 is extended as

45 shown through the cover plate 12 and is pro-

50 vided at its extreme outer end with a knurled wheel 16 by means of which said minute hand

55 may be adjusted when desired. An adjusting sleeve 17 is loosely mounted as shown on the

shaft 15 and carries a radially extending control arm 18 telescoping with an extension 19 pro-

55 vided at its outer end with a head 20 having

sight opening 21 therein and an indicator point

22 at the outer central part of said opening. A

pin 23 is provided on the rear side of the head

20 which operates in the groove 11 and a fric-

55 tion washer 24 is interposed between the hub of

the minute hand 14 and the hub of the sleeve 17 thereby frictionally connecting the sleeve 17 with the shaft 15 so that the control arm 18—19 will always move with the minute hand of the clock mechanism. The sleeve 17 is provided as 5 shown, outside of the cover plate 12 with a knurled wheel 17' whereby the control arm 18—19 may be readily adjusted, from outside the cover plate, with reference to the minute hand 14.

A swinging lever 25 is pivoted as shown at the 10 rear of the clock face and is provided with an outwardly extending arm 26 operating in a segmental slot 27 in the clock face, said arm 26 thus extending outwardly into the path of the pin 23 on the head 20 of the control arm 18—19. 15

A weighted arm 28 is attached, as best shown in Fig. 6, to the swinging lever 25 and serves to hold said lever normally in its initial position before being engaged by the pin 23. By this arrangement, it will be noted, that when 20 the pin 23 is moved upwardly in the groove 11 until it passes the slot 27, it will engage the protruding end of the arm 26 and thus carry the swinging lever 25, with it. The swinging lever 25 is also provided with a rearwardly extending electric contact arm 29 having a spring extension 30 which is set as shown in the path of the stationary electric contact 31 having depressed and beveled nose or tip 32, best shown in Fig. 5. The stationary contact 31 is connected 30 by a wire 33 with an electric alarm buzzer 34 which in turn is connected by wire 35 with one of the leads 36 for the clock mechanism. The contact arm 29—30 is likewise connected by a wire 37 with the other electric lead 38 of the 35 clock mechanism so that whenever the extension 30 makes rubbing contact with the stationary electric contact 31 the circuit through the buzzer 34 is closed thus sounding an alarm signal.

40 In use and operation, when it is desired to control the length of a cooking or other operation, the control arm 18—19 is adjusted by means of the wheel 16 the required number of minutes away from the twelve o'clock point on the clock dial. Thus in the position of the parts indicated 45 in Fig. 1, the control arm 18—19 is shown as set twelve and one-half minutes away from the twelve o'clock point on the clock dial. As the minute hand shaft 15 moves under the usual operation of the clock mechanism, the control arm 50 18—19 will be carried along with it and when the pin 23 engages the arm 26 the contact 30 will be swung into engagement with the contact 31 thus closing the circuit to the buzzer 34 and sounding the alarm and notifying the operator that the 55

allotted time has elapsed. Obviously, the further the control arm 18 is thus set away from the twelve o'clock point on the clock dial, the longer the time consumed before the same is carried 5 with the minute hand into operative contact with the arm 26. Should it be desired to set the control arm for a period longer than sixty minutes, the wheel 17 is manipulated to carry the pin once entirely around the clock dial and thence into the 10 inner portion of the groove 11, as illustrated by the full line position of said control arm shown in Fig. 2, said control arm being here set to require approximately 67 minutes before the pin 23 will be brought into contact with the arm 26. 15 Likewise by setting the control arm of the pin 23 even further along in the groove 11, the same may be set for the lapse of a greater time up to substantially the full two hour or one hundred and twenty minute limit. As the arm 26 is thus 20 engaged by the pin 23, the spring contact 30 is moved into engagement with the beveled nose 32 of the contact 31, thereby riding up over the top of said contact 31 and closing the circuit through the alarm buzzer 34 as long as this contact is 25 maintained. The arrangement is such that the contact 30 rides off of the end of the contact 31 just before the arm 26 reaches the end of the movement permitted by slot 27, at which time the said arm 30 springs downwardly below the contact 31 as indicated by the dotted lines in Fig. 5. 30 When arm 18 is reset, the weighted arm 28 operates automatically to return the contact 30 to initial position, as indicated by the full lines in Fig. 5, thus resetting the mechanism for another 35 operation when desired. By this arrangement a simple and effective timer is provided which may be utilized in cooking or other operations; which is accurate and dependable in use; in which the control arm may be readily set from 40 outside of the clock mechanism and without disturbing the clock mechanism; in which the ordinary

hands of the clock may be readily set without disturbing the timer mechanism; and is of simple construction and highly efficient in use.

While I have illustrated and described the preferred form of construction for carrying the invention into effect, this is capable of variation and modification without departing from the spirit of the invention. I therefore do not wish to be limited to the precise details disclosed, but desire to avail myself of such variations and modifications as fall within the scope of the appended claims.

I claim:

1. The combination with a clock shaft, of a control arm mounted thereon; a spring electric contact shiftable by said control arm when it reaches a predetermined point; a stationary electric contact set in the middle portion of the path of and arranged to deflect said spring contact out of its normal path; and means for automatically 15 returning said spring contact to initial position.

2. The combination with a clock shaft, of a control arm frictionally adjustable thereon; a swinging lever arranged to be moved by said control arm when it reaches a predetermined point; 25 a spring electric contact carried by said lever; a stationary electric contact set in the middle portion of the path of said spring contact; and a weight automatically returning said swinging lever to initial position.

3. The combination with a clock shaft, of a control arm frictionally adjustable thereon; a swinging lever arranged to be moved by said control arm when it reaches a predetermined point; 35 a spring electric contact carried by said lever; a stationary electric contact set in the middle portion of the path of said spring contact and arranged to deflect said spring contact out of its normal path; and a weight automatically returning 40 said swinging lever to initial position.

JEROME DE HAES.
